UNITED STATES PATENT OFFICE.

JOSEPH BERGE AND LOUIS B. BERGE, OF FLINT, MICHIGAN, ASSIGNEES TO A. C. SPARK PLUG COMPANY, OF FLINT, MICHIGAN, A CORPORATION OF MICHIGAN.

ELECTRICAL CONNECTER FOR SPARK PLUGS.

Application filed April 11, 1919. Serial No. 289,269.

To all whom it may concern:

Be it known that we, JOSEPH BERGE and LOUIS B. BERGE, both citizens of the United States of America, residing at Flint, in the county of Genesee and State of Michigan, have invented certain new and useful Improvements in Electrical Connecters for Spark Plugs, of which the following is a specification, reference being had therein to the accompanying drawings.

The invention relates to electrical connectors particularly designed for use in connection with spark plugs and the invention consists in the construction of the coupling as hereinafter set forth.

In the drawings:

Figure 1 is an elevation of a spark plug showing the connector in engagement therewith;

Figure 2 is a perspective view of the coupling members detached;

Figure 3 is an enlarged vertical sectional view showing the engagement of the connector with the plug terminal;

Figure 4 is a view, partly in elevation and partly in section, showing an alternative form of the invention;

Figure 5 is a view in side elevation of another form of the invention;

Figure 6 is a sectional view taken on line 6—6 of Figure 5.

Describing first the construction shown in Figures 1, 2 and 3, A is a spark plug having the insulator B and an electrode C projecting from the outer end of said insulator to form a terminal post. This post is provided with a groove C' and with a tapered or rounded outer end C². D is the insulated conductor for the terminal connector, and E is a coupling at the end of said conductor for engaging the post C.

In order that the conductor D may be arranged in axial alignment with the spark plug the coupling E is in the form of a resilient socket member which may be sleeved over the post C and will be yieldably held from disengagement therefrom. We have, therefore, devised a simple construction of such a coupling as follows: F and F' are segmental members, preferably stampings, which are adapted to embrace the insulation on the conductor D on opposite sides thereof. These members are formed with a shoulder G and a portion H extending for-

wardly therefrom of slightly smaller diameter and substantially corresponding internally to the external diameter of the post C. I is a ferrule member for fitting over the shank ends of the members F and F' to clamp the same against the insulation of the conductor D, and I' is an inturned flange on the ferrule for engaging the shoulder G.

To mount the coupling upon the conductor a portion J of the stranded metallic conductor is bared of the insulation and is divided and then turned backward over the outer surface of the insulation, and preferably upon diametrically opposite sides thereof. The members F and F' are then placed against the return-bent ends of the bared portions J, after which the ferrule I is engaged with the outer ends of said members and pressed on the shanks thereof so as to force the same inward against the insulation with considerable pressure. This will cause the imbedding of the conductor J in the insulation and will compress the latter so that the ferrule is substantially flush with the surface of the insulation beyond the same. The members F and F' are also provided with prongs K at the inner ends of the shanks, which are pressed into the insulation and form a locking engagement therewith. Thus the coupling when assembled will be firmly attached to the insulated conductor and will be in good electrical connection with the metallic conductor thereof. The members F and F' are further provided with inwardly pressed portions L which are so located that when the coupling is sleeved upon the post C, the projections L will engage with the groove C'.

To positively prevent accidental disengagement of the ferrule I from the coupling, said ferrule may be formed with a pair of inwardly deflected tongues L' which when the parts are assembled, will shape into apertures L², respectively formed in the shank portions of the coupling. Thus, the ferrule will be effectively locked against removal.

With the construction as described, in use the connector may be quickly attached to or detached from the plug by telescopically engaging the coupling with the post C. The inwardly extending portions L in passing over the outer end of the post will expand the socket, but this is permitted by the yield-

able character of the insulation to which the shanks of the members F and F' are clamped. Also the resiliency of this insulation will cause the portions L to snap into engagement with the groove C' and therefore to hold the coupling from accidental disengagement. Thus a resiliently expandable socket coupling is formed without any flexing of the metallic members thereof, which, 10 on account of the curved cross-section, would be difficult to accomplish. The construction is also one which is exceedingly inexpensive to manufacture and which may be quickly assembled.

15 The form of the invention disclosed in Figure 4 is quite similar to the construction already described, the only difference being that the coupling member is of an elbow form, having a ninety degree bend, whereby 20 the conductor may lead laterally to the spark plug instead of having an axial relation thereto.

In the construction shown in Figures 5 and 6, the two coupling members M have 25 complementary cylindrical portions M' for engaging the terminal post N of a spark plug, the axis of the portions M' being transverse to that of the coupling itself so that the latter may engage a conductor O laterally approaching the spark plug. In this 30 construction the ferrule R, since it cannot be passed over the portions M' of the coupling, must be slipped on the conductor O prior to engaging the members M therewith 35 and is shifted toward the adjacent end of the conductor to engage it with the members M. The ferrule R, in this form of the invention, is preferably formed of fiber and has the internal shoulder R' to engage the ends 40 of the coupling members M.

What we claim as our invention is:—

1. In an electrical connector, the combination with a conductor having an elastic insulation, of an expandable socket coupling member at the end of said conductor, electrically connected with said conductor and comprising substantially non-flexible segments overlapping the end of the insulation, and means clamping said segments upon said insulation, relative yielding of the segments being provided for by the elasticity of the insulation. 45

2. In an electrical connector, the combination with an insulated conductor, of a pair of complementary segments having shank portions overlapping the end of the insulation, the opposite ends of said segments forming an expandable tubular socket, said segments being of a contour to produce rigidity throughout their lengths, and means 50 for clamping said shank portions upon the insulation of said conductor, relative yielding of the segments being provided for by the resiliency of the insulation. 55

3. In an electrical connector, the combination with a conductor having elastic insulation, of a tubular member comprising separate complementary segments transversely curved throughout their lengths, and means for clamping said segments upon the insulation of said conductor, one end of said tubular member overlapping and being secured by said means to the insulation of said conductor and the other end forming an expandable socket. 60

In testimony whereof we affix our signatures.

JOSEPH BERGE.
LOUIS B. BERGE.
